UNITED STATES PATENT OFFICE.

PAUL KLIMOWICZ, OF STEVENS POINT, WISCONSIN.

CHANGEABLE SIGN.

Application filed October 28, 1927. Serial No. 229,464.

The invention generally relates to signs of the changeable letter or character type, and primarily has for its object to provide a new and improved sign structure of neat appearance and readily changeable as regards its displayed indicia, with a minimum of effort and in a manner eliminating the display of unsightly mounting holes, grooves or other recesses.

In its more detailed nature the invention has for its object to provide a sign of the type stated comprising a sign body including a relatively soft prick camouflaging filler body having good retaining qualities, and suitable sign display characters each having spaced mounting prongs insertible into the filler body and so spaced uniformly relatively to the vertical dimensions of the said characters that when they are positioned in alignment, alignment of the characters is assured.

With the above and other objects in view that will hereinafter appear, the invention still further resides in the novel details of construction, combination and arrangement of parts, all of which will be first fully described, then be particularly pointed out in the appended claims, reference being had to the accompanying drawing, in which:

Figure 1 is a face view of an assembled sign.

Figure 2 is an enlarged cross section of an edge portion of the sign.

Figure 3 is a perspective view of a dismounted character.

Figure 4 is an edge view of a dismounted character.

Figures 5, 6 and 7 are detail perspective views illustrating several forms of mounting prongs.

In carrying out the principles of my invention I provide a sign board body 1 of any suitable material such as tin plate, wood or wall board but preferably the latter because of its economical nature and being free from tendency to warp. The edges of the body 1 may be beveled as at 2 if desired and the edges of said board are provided with an upstanding border strip 3 preferably of harder material such as wood or straw board and which serves to provide and define a depression in which is provided a filler body 4 of soft material having good prong retaining qualities for a purpose later to be described. The filler body may be built up of any suitable material such as cotton bat-

ting, felt, special blotting paper, or paper mill wood pulp, and has the exposed face thereof covered with a fabric sheet 5 of a texture or having the quality of camouflaging prong pricks and therefore providing for maintaining an unbroken surface presented to view and not marred by holes, grooves, slots or any of the other usual character mounting recesses such as are employed in common types of signs of this character.

The characters of which the sign is changeably composed are indicated at 6 and it is to be understood that these characters comprise letters, numerals, punctuation marks, and fancy designs of various sizes, shapes and styles such as are usually employed in the building up of changeable signs.

Each character 6 is provided with a pair of prongs 7 projecting from the rear face thereof and having their heads embedded in the body of the characters as at 8, the letters preferably being constructed of cast metal or other suitable material such as will provide a neat appearance and for the convenient molding of the prongs' heads therein when the characters are being formed. As will be observed by reference to Figures 3 and 4 of the drawings the prongs bear spaced relation in and project from the characters and also bear fixed relation with the upper and lower limits of the letters so that when the prongs are arranged in alignment, such alignment of the prongs will assure the desired alignment of the characters.

Between the fabric covering and prick camouflaging sheet 5 and the filler body 4 I mount a thin sheet of stiff, strong paper 9 which not only serves to hold the filler in shape and against tendency to bulge in places, but also to more efficiently retain the letter mounting prongs when the letters are mounted.

It will also be observed by reference to Figures 2, 4 and 5 of the drawings that the prongs carried by each letter are uneven in length, one being a long mounting prong for deeply penetrating the sign board to secure the letter, and the other being a very short prong adapted to penetrate the sheet 5 only and serving merely to hold the letter against turning about the mounting point. The prongs are preferably united at their embedded ends to form U-shaped members but may be separate and constructed as indicated in Figures 6 and 7 if desired.

By providing the soft filler body and the prong prick camouflaging sheet covering therefor the sign may be varied and changed as often as desired and will always retain its fresh and neat appearance without accumulating an unsightly array of holes or other grooves such as appear in common types of signs now in use.

By providing the pair of prongs projecting from each character, means is not only provided for more securely holding the characters to position but the said pair of prongs also serve to prevent any tendency of the characters to pivot on their mounting and become mis-aligned. By making the prongs uneven in length as described the full quality of stabilizing the letters against turning is acquired while making but a single prick in the board proper to mount each letter. Obviously this feature substantially doubles the life of the sign board.

Also, by providing the strong paper under-sheet the neat appearance of the sign is better retained over a long period and it is possible to employ a cheaper grade of filler body material without sacrificing efficiency in the way of letters holding quality.

From the foregoing description, taken in connection with the accompanying drawings, it is thought that the novel details of construction, the manner of use and the advantages of my invention will be readily apparent to those skilled in the art to which it relates.

35 What I claim is:

1. A sign of the character described comprising a body, an upstanding border edge forming a depression within its confines, a soft filler in the depression, a fabric sheet

covering the exposed face of the filler and 40 having prong prick hiding qualities, a sheet of thin relatively stiff paper interposed between the fabric sheet and the soft filler, and sign forming characters having mounting prongs removably embedded in the filler. 45

2. A sign of the character described comprising a body, an upstanding border edge forming a depression within its confines, a soft filler in the depression, a fabric sheet covering the exposed face of the filler and 50 having prong prick hiding qualities, a sheet of thin relatively stiff paper interposed between the fabric sheet and the soft filler, and sign forming characters having mounting prongs removably embedded in the filler, 55 said fabric sheet surrounding the marginal edges of said filler and extending beneath the filler to be in engagement with said body and its border edge.

3. A sign of the character described comprising a body, an upstanding border edge forming a depression within its confines, a soft filler in the depression, a fabric sheet covering the exposed face of the filler and having prong prick hiding qualities, a sheet 60 of thin relatively stiff paper interposed between the fabric sheet and the soft filler, sign forming characters having mounting prongs removably embedded in the filler, 65 each of said characters' prongs comprising a long one and a short one, the long prong being of a length substantially equal to the combined thickness of said filler, said fabric and said paper sheet, and the short prong being of a length substantially equal to the 70 thickness of said fabric. 75

PAUL KLIMOWICZ.
